CLAIM

The ornamental design for a distal extension for a blood pump system, as shown and described.

DESCRIPTION

FIG. 1 is a top, rear, right side perspective view of a distal extension for a blood pump system according to a first embodiment of our new design;

FIG. 2 is a right side elevation view thereof;

FIG. 3 is a left side elevation view thereof;

FIG. 4 is a rear side elevation view thereof;

FIG. 5 is a front side elevation view thereof;

FIG. 6 is a top plan view thereof;

FIG. 7 is a bottom plan view thereof;

FIG. 8 is a bottom, front, right side perspective view thereof;

FIG. 9 is a top, rear, right side perspective view of a second embodiment thereof;

FIG. 10 is a right side elevation view of FIG. 9;

FIG. 11 is a left side elevation view of FIG. 9;

FIG. 12 is a rear side elevation view of FIG. 9;

FIG. 13 is a front side elevation view of FIG. 9;

FIG. 14 is a top plan view of FIG. 9;

FIG. 15 is a bottom plan view of FIG. 9;

FIG. 16 is a top, rear, right side perspective view of a third embodiment thereof;

FIG. 17 is a right side elevation view of FIG. 16;

FIG. 18 is a left side elevation view of FIG. 16;

FIG. 19 is a rear side elevation view of FIG. 16;

FIG. 20 is a front side elevation view of FIG. 16;

FIG. 21 is a top plan view of FIG. 16; and,

FIG. 22 is a bottom plan view of FIG. 16.

The dot-dash broken lines represent boundaries of the

claimed design and form no part thereof. All other broken

(Continued)

lines illustrate portions of the distal extension for a blood pump system that forms no part of the claimed design.
